Attest
John C. Osgood.

UNITED STATES PATENT OFFICE.

ROBERT C. OSGOOD, OF CLAREMONT, NEW HAMPSHIRE, ASSIGNOR TO SULLIVAN MACHINERY COMPANY, A CORPORATION OF MASSACHUSETTS.

HAULING MECHANISM.

Application filed January 14, 1922. Serial No. 529,104.

My invention relates to hauling mechanisms, and more particularly to hauling mechanisms of the power driven capstan type.

5 An object of my invention is to provide an improved haulage mechanism. Another object of my invention is to provide an improved haulage mechanism of the capstan type in which, by the use of an improved 10 relation between the driving motor and the winding element, a very advantageous construction can be produced. A still further object of my invention is to provide an improved winding mechanism of very simple 15 construction and in which the machine work may be reduced to a minimum. Other objects and advantages of my invention will hereinafter more fully appear.

In the accompanying drawings I have 20 shown for purposes of illustration one form which my invention may assume in practice.

In these drawings,—

Fig. 1 is a central vertical section, with 25 parts in elevation, through the illustrative embodiment of my invention.

Fig. 2 is a transverse section on the line 2—2 of Fig. 1 with parts broken away to two lower sections to show details of construction.

30 Fig. 3 is a transverse section on the line 3—3 of Fig. 1.

In the illustrative embodiment of my invention, it will be noted to comprise a casing member 1 which is bored to provide 35 intercommunicating rotor chambers 2 and 3 which are closed at their lower ends by a common closure plate 4 in which bearings for the lower ends of intermeshing rotors 5 and 6 are provided. The rotors 5 and 6 40 are provided with intermeshing tooth blades cooperating to form expansion chambers to which fluid pressure may be admitted to rotate said rotors. The casing 1 is divided somewhat above its middle by a second 45 transverse plate constituting the other end plate for the rotor chambers 2 and 3, this plate being designated 7 and furnishing bearings for the upper ends of the rotor shafts 8 and 9 and supporting the lower end 50 of a shaft 10 which is hereinafter referred to. The upper end of the casing 1 is closed by cover plate 11 provided with a stationary shaft or journal member 12 upon which there is rotatably mounted, by means of suitable 55 bearings 13, a capstan member 14. This

capstan member is provided with a depending collar or flange 15 within which an internal gear 16 is formed and which cooperates by means of a ring 17 to prevent access of moisture to the interior of the 60 casing. Admission to the motor is accomplished by way of an inlet passage 18 and an admission port 19 and exhaust is to chambers 20 and 21 at the ends of the rotors, these chambers being connected by a passage 22 and the exhaust air being discharged through a port 23 to a hollow chamber 24 in the base of the frame 1 and thence passing by way of the port 25 to the atmosphere. The rotor shaft 8 is provided with 70 a pinion 26 which meshes with a larger pinion 27 mounted on the shaft 10, and likewise mounted on the shaft 10 is a second smaller pinion 28. The latter meshes with a larger gear 29 which serves to drive a 75 shaft 30 journaled in the cover plate 11, upon which a pinion 31 is mounted outside the cover plate 11, but within the space between the member 14 and the top of the motor casing proper. A pinion 32 journaled 80 upon a stud 33 secured to the top 11 of the frame 1 meshes with the internal gear 16 and serves upon rotation of the rotor to drive the haulage member.

The mode of operation of this device will 85 be readily apparent from the foregoing description. Fluid pressure having been admitted by way of the passage 18 passes by way of port 19 to the tooth pockets formed by the intermeshing tooth blades on the 90 rotors and this fluid pressure acts expansively therein and then exhausts to the chambers 20 and 21 and from these by the port 23 to the space 24 and by port 25 to the atmosphere. As the rotors rotate, the 95 pinion 26 is driven and through pinions 27, 28, 29, 31 and 32, the internal gear 16 is driven and so the haulage member 14 is caused to rotate. A flexible winding member, herein designated 35, may have a couple 100 of turns taken around the capstan member 14 and will then be hauled in the desired direction, depending upon the direction in which it is wound upon the member 14. By reason of the motor used, a very powerful 105 torque can be obtained and owing to the construction of the entire device the same is rendered substantially moistureproof and of very rugged construction.

While I have in this application specifi- 110

5 cally described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

base casting housing a motor and provided with an upwardly extending stem and a coaxial laterally projecting annular flange, the interior of said casting comprising a motor compartment and a reduction gearing compartment, a winding drum journaled wholly on said stem and provided with an enlarged base which terminates in a cylindrical portion coaxial with said annular flange, interengaging connections forming a joint in a horizontal plane between the cylindrical portion and the annular flange, whereby an enclosed chamber is formed between the drum and the top of the casting, and operative connections between the motor and the drum including reduction gearing in said reduction gearing chamber and in said last mentioned chamber.

5. In a power driven capstan, an upright supporting base providing a transversely extending supporting surface upon which the base is adapted to stand, said base forming a motor casing enclosing a motor and having a closed chamber at the top and a motor exhaust chamber at the bottom thereof, reduction gearing driven by said motor and disposed in said top chamber, and a rotatable rope winding member carried by and journaled on said base at the upper end of the latter and provided with an enlarged lower portion which terminates in a cylindrical portion carrying an internal gear, said internal gear being driven by said reduction gearing and said base providing bearing support for said rotatable rope winding member wholly inside the latter.

6. In a power driven capstan, an upright supporting base providing a transversely extending supporting surface upon which the base is adapted to stand, said base forming a motor casing enclosing a motor and having a closed chamber at the top and a motor exhaust chamber at the bottom thereof, reduction gearing driven by said motor and disposed in said top chamber, and a rotatable rope winding member carried by and journaled on said base at the upper end of the latter and provided with an enlarged lower portion which terminates in a cylindrical portion forming with the top of said supporting base a closed chamber, said cylindrical portion carrying an internal gear driven by said reduction gearing and said base providing bearing support for said rotatable rope winding member wholly inside the latter. 115

In testimony whereof I affix my signature.

ROBERT C. OSGOOD.
